(57) CLAIM

The ornamental design for a nose and ear cleaning device, as shown and described.

DESCRIPTION

FIG. 1 is a perspective view of a nose and ear cleaning device;

FIG. 2 is another perspective thereof, shown in an alternative position;

FIG. 3 is another perspective view thereof, shown in an alternative position;

FIG. 4 is a front and top perspective view of a first piece of the nose and ear cleaning device;

FIG. 5 is a rear and bottom perspective view thereof;

FIG. 6 is a front elevation view thereof;

FIG. 7 is a rear elevation view thereof;

FIG. 8 is a left side elevation view thereof;

FIG. 9 is a right side elevation view thereof;

FIG. 10 is a top plan view thereof;

FIG. 11 is a bottom plan view thereof;

FIG. 12 is a front and top perspective view of a second piece of the nose and ear cleaning device;

FIG. 13 is a rear and bottom perspective view thereof;

FIG. 14 is a front elevation view thereof;

FIG. 15 is a rear elevation view thereof;

FIG. 16 is a left side elevation view thereof;

FIG. 17 is a right side elevation view thereof;

FIG. 18 is a top plan view thereof;

FIG. 19 is a bottom plan view thereof;

FIG. 20 is a front and top perspective view of a third piece of the nose and ear cleaning device;

FIG. 21 is a rear and bottom perspective view thereof;

FIG. 22 is a front elevation view thereof;

FIG. 23 is a rear elevation view thereof;

FIG. 24 is a left side elevation view thereof;

FIG. 25 is a right side elevation view thereof;

FIG. 26 is a top plan view thereof; and,

FIG. 27 is a bottom plan view thereof.
